(57) **CLAIM**

I claim the ornamental design for a raised potting bed planter, as shown and described.

DESCRIPTION

FIG. 1 illustrates a top perspective view of the raised potting bed planter.

FIG. 2 illustrates a side view of the raised potting bed planter of FIG. 1.

FIG. 3 illustrates a top view of the raised potting bed planter in FIG. 1.

FIG. 4 illustrates a side view of the raised potting bed planter in FIG. 1.

FIG. 5 illustrates a bottom view of the raised potting bed planter in FIG. 1; and,

FIG. 6 illustrates a side view of the raised potting bed planter of FIG. 1.

The broken lines depict portions of the raised potting bed planter, that form no part of the claim.
